UNITED STATES PATENT OFFICE

169,165

PHOTOGRAPHIC CAMERA HOUSING UNIT

Arthur C. Mueller, Des Plaines, Ill., assignor to
Bell & Howell Company, Chicago, Ill., a corpora-
tion of Illinois

Application June 9, 1951, Serial No. 15,487

Term of patent 14 years

(Cl. D61—1)

To all whom it may concern:

Be it known that I, Arthur C. Mueller, a citizen of the United States of America, residing at Des Plaines, State of Illinois, have invented a new, original, and ornamental Design for a Photographic Camera Housing Unit, of which the following is a specification, reference being had to the accompanying drawing, forming a part hereof.

In the said drawing:

Figure 1 is a front perspective view of a photographic camera housing unit embodying my new design;

Figure 2 is a rear perspective view thereof; and

Figure 3 is a front perspective view taken from the opposite side of Figures 1 and 2.

I claim:

The ornamental design for a photographic camera housing unit, as shown.

ARTHUR C. MUELLER.
